(57) **CLAIM**

I claim the ornamental design for a combination toilet with flushless urinal, as shown and described herein.

DESCRIPTION

FIG. 1. Is a perspective view of my combination toilet with flushless urinal;

FIG. 2. Is a front view thereof;

FIG. 3. Is a rear view thereof;

FIG. 4. Is a top view thereof;

FIG. 5. Is a bottom view thereof;

FIG. 6. Is a right view thereof; and,

FIG. 7. Is a left view thereof.

The broken line portions of the disclosure are for illustrative purposes only and form no part of the claimed design.
